UNITED STATES PATENT OFFICE.

WILLIAM H. RICHARDS, OF CANONSBURG, PENNSYLVANIA.

REWORKING TUBES.

No. 904,451.

Specification of Letters Patent.

Patented Nov. 17, 1908.

Application filed April 14, 1908. Serial No. 427,015.

To all whom it may concern:

Be it known that I, WILLIAM H. RICHARDS, citizen of the United States, residing at Canonsburg, county of Washington and 5 State of Pennsylvania, have invented certain new and useful Improvements in Reworking Tubes, of which the following is a specification, reference being had therein to the accompanying drawing.

10 This invention relates to an apparatus for reworking pipes, tubes and cylindrical bodies into plate material, whereby the superior quality of metal in scrap material of this character may be utilized.

15 The invention has for an object to provide means for heating the tubes, for splitting and flattening said tubes while heated, and subsequently rolling the flattened plate into the desired thickness for future use.

20 A further object of the invention is to provide a plow having a cutter at its apex and curved rearwardly extending faces whereby the tube is slit and pressed into substantially flat form at a single operation, together with means for presenting the plate thus formed to a rolling mill at an angle to the longitudinal axis of the tube.

25 Other and further objects and advantages 30 of the invention will be hereinafter fully set forth and the novel features thereof defined by the appended claims.

In the drawing:—Figure 1 is a plan showing an application of the invention; Fig. 2 is a vertical section on line 2—2, Fig. 1; Fig. 3 is an enlarged plan of the plow and tube bed; Fig. 4 is a side elevation of these parts; Fig. 5 is a detail perspective of the tube as split and flattened.

40 Like numerals refer to like parts in the several views of the drawing.

The numeral 10 designates a furnace which may be of any desired construction suitable for heating tubes, and is here shown 45 as a down draft furnace having fire boxes 11 at opposite sides and chimney 12 so that the products of combustion pass downward through the chamber 13 which is provided with an inclined floor 14 apertured at 15 and adapted to support the pipes 16, as shown in Fig. 2. From this chamber a flue 17 extends to the chimney 12. The tube chamber is provided with an inlet door 18 and a discharge 19 at the opposite side thereof, the latter communicating with the platform 20 by which the heated tube is delivered upon the bed 21 extending parallel to the length

of the tube and provided, if desired, with a recess 22 to retain the tube in proper position. At one end of this bed a plow 23 is disposed and adapted to reciprocate for the 60 length of the bed, it being propelled by any desired power, for instance, the piston rod 24 extending to the power cylinder 25. This plow is provided at its apex with a removably mounted cutter 26 which may be inter- 65 changed for different sizes of material and is preferably inclined downward from the top so as to assist by its shearing action in holding the tube upon the bed during the splitting thereof. The plow is provided at 70 each side with rearwardly extending curved faces 27 merging into a horizontal plane parallel to the bed and at the point a flattening roller 28 is pivotally mounted in the opposite sides of the plow so as to traverse 75 and flatten the heated tube while holding it in firm contact with the bed 21.

For the purpose of retaining the tube or pipe 16 against longitudinal movement, any desired holding device may be used, for instance, a gripper 29 extending upward from the bed at one end of the tube recess and adapted to enter the tube, as shown in Figs. 1 and 2. This gripper is carried by the rod 30 and normally held out of contact by the 80 spring 31 extending from the rod to the casting 32 thereof, while the gripper may be firmly held by a treadle connection, as shown at 33 or any preferred means.

In the operation of the invention it is de- 90 sirable that the plate formed from the tube should be rolled at an angle to the longitudinal axis of the tube, and for that purpose the bed is normally disposed at an angle to the rolls 34 comprising a portion of the rolling 95 mill and is adapted to rotate into a position parallel with these rolls, as shown by dotted lines in Fig. 1. Various means may be used to secure this movement, one form of which comprises the sector 35 carried by the bed 100 and adapted to engage the gear 36 which is driven from the geared shaft 37. For the purpose of changing the direction of travel of the bed a sleeve 38 is splined upon the driving shaft 39 which is rotated from any 105 suitable source of power applied at the pulley 40 or may comprise the shaft of one of the mill rolls. This sleeve is provided with oppositely disposed bevel gears 41 and 42 either of which may be thrown into mesh 110 by the shifting lever 43.

In the operation of the invention, the tube

is first heated to the desired temperature and then secured upon the bed, when the plow advances and simultaneously cuts and bends the softened material of the tube from the 5 cylindrical into a substantially flat form, this being materially assisted by the flattening roller at the rear. The action of this plow and roller also removes from the inner surface of the former tube all oxids, rust 10 and other impurities which would be detrimental and impracticable to use in the subsequent rolling action. The plate is now released from the gripper and the bed rotated to a position parallel with the mill rolls into 15 which the plate is introduced and rolled to the desired thickness. It will be seen that this construction presents means by which scrap pipes tubes and cylindrical bodies containing the best quality of material may be 20 practically utilized for plates and the splitting and flattening readily accomplished by a single operation as the tube when heated can be readily split by the cutter and bent or flattened by the plow in its passage there- 25 over, as shown in Fig. 5.

Having described my invention and set forth its merits, what I claim and desire to secure by Letters Patent is:—

1. In a machine for reworking tubes, a 30 base for supporting a tube, means for simultaneously slitting and bending outward in opposite directions the slitted edges of the tube, and means in the rear of the slitting means having a face substantially parallel to the base and adapted to force the outwardly bent tube into contact therewith.

2. In a machine for reworking tubes, means for supporting a tube, and a slitter provided with oppositely inclined portions extending 40 toward the supporting means and outwardly and rearwardly and adapted for flattening the tube into contact with the supporting means during the slitting action.

3. In a machine for reworking tubes, 45 means for supporting a tube, a reciprocating slitter provided with oppositely inclined portions extending toward the supporting means and outwardly and rearwardly and adapted for bending the slitted edges of the 50 tube in opposite directions, and means in the rear of the slitting means having a face substantially parallel with the supporting means and adapted to force the outwardly bent tube into contact therewith.

4. In a machine for reworking tubes, a 55 heating device, rolling means, a carrier adapted to support a tube and movable from alinement with the delivery from said device to the intake of said means, and a slitting means operable upon the tube on said carrier.

5. In a machine for reworking tubes, a 60 heating device, rolling means, a carrier adapted to support a tube and movable from alinement with the delivery from said car-

rier to the intake of said means, a slitting means disposed relative to the carrier for travel longitudinally of the tube thereon, means for holding said tube against longitudinal movement upon the carrier, and 70 means for retracting said holding means from the path of said tube.

6. In a machine for reworking tubes, means for supporting a tube, and a co-operating flattening plow above said means and 75 having at its apex a slitting cutter and rearwardly, downwardly and outwardly inclined opposite bending faces extending therefrom.

7. In an apparatus for reworking tubes, a bed, a traveling plow disposed above said 80 bed and having a vertically disposed blade at its apex and provided upon its lower face with downwardly curved portions extending rearwardly and downwardly from said apex.

8. In an apparatus for reworking tubes, a 85 bed, a plow disposed above said bed and having a cutter at its apex and provided upon its lower face with downwardly curved portions extending rearwardly and outwardly from said apex, and a surface at the lower 90 portion of the curved faces adjacent the bed to force a flattened tube in contact with said bed.

9. In an apparatus for reworking tubes, a 95 support, a plow located above the same and adapted to engage a tube when disposed thereon, said plow having at its apex a downwardly and rearwardly inclined cutter and at the opposite sides thereof inclined under faces extending downwardly, out- 100 wardly and rearwardly from the apex.

10. In an apparatus for reworking tubes, a furnace, a bed disposed parallel to the discharge thereof, and a slitting cutter adapted to traverse said bed parallel with the furnace 105 discharge and having means for forcing a flattened tube in contact therewith.

11. In an apparatus for reworking tubes, a furnace, a bed disposed parallel to the discharge therefrom, a slitting cutter adapted to traverse said bed, a rolling mill disposed at an angle to the travel of said cutter, and means for shifting said bed parallel to the 110 rolls of said mill.

12. In an apparatus for reworking tubes, 115 a feeding device, a movable bed disposed parallel to the discharge thereof, a metal working means, means for shifting said bed from said feed device to said means, a gripper disposed upon said bed to engage one end of a tube thereon, means for operating said gripper, and a tube slitting device adapted to traverse said bed in alinement with said gripper.

13. In an apparatus for reworking tubes, 120 a feeding device, a metal working means, a bed disposed to travel from said feed device to said means, and a tube slitter adapted to traverse said bed in a path transverse to the travel of the bed.

14. In an apparatus for reworking tubes, a bed pivotally mounted at one end, a cutter mounted upon a stationary support and adapted to traverse the path of travel of said bed, a sector carried by said bed, and a driving gear engaging the sector to rotate the bed, a sector carried by said bed, a driving gear engaging said sector to rotate the bed, and a gripper disposed at the axis of said bed to retain a tube thereon. 15
- 5 15. In an apparatus for reworking tubes, a bed pivotally mounted at one end, a cutter mounted upon a stationary support and adapted to traverse the path of travel of said

bed, a sector carried by said bed, a driving gear engaging said sector to rotate the bed, and a gripper disposed at the axis of said bed to retain a tube thereon.

In testimony whereof I affix my signature in presence of two witnesses.

WILLIAM H. RICHARDS.
